UNITED STATES PATENT OFFICE.

ARTHUR H. BONNELL, OF BROOKLYN, NEW YORK.

DESIGN FOR A TILE.

SPECIFICATION forming part of Design No. 27,109, dated May 25, 1897.

Application filed March 29, 1897. Serial No. 629,865. Term of patent 14 years.

To all whom it may concern:

Be it known that I, ARTHUR H. BONNELL, a citizen of the United States, residing at Brooklyn, in the county of Kings and State 5 of New York, have invented and produced a new and original Design for a Tile, of which the following is a specification, reference being had to the accompanying drawings, forming a part thereof, in which—

o Figure 1 is a plan view of a tile embodying my design, and Fig. 2 is a section on the line 2 2 of Fig. 1.

The leading feature of the design consists in a tile the edge of which is provided with 5 alternately concaved and convexed portions, the radii being approximately alike and the segments of the convex portions having a common center.

Referring to the drawings, 1 designates a

tile having its edge provided with three concaved portions 2 and three convex portions 3. The length or the radii of the convex portions and the concave portions will be equal one with the other, and when a series of tile are arranged together to form a floor or other 25 structure the cement will be extended upward between adjacent surfaces of adjacent tiles.

The tiles forming a floor or other structure may, if desired, be of different colors. 30

I claim—

A design for a tile, substantially as shown and described.

ARTHUR H. BONNELL.
